US00D885829S

(12) **United States Design Patent** (10) **Patent No.:** **US D885,829 S**
Bodum (45) **Date of Patent:** **** Jun. 2, 2020**

(54) **LID**

(71) Applicant: **PI-Design AG**, Triengen (CH)

(72) Inventor: **Jorgen Bodum**, Meggen (CH)

(73) Assignee: **PI-Design AG**, Triengen (CH)

(**) Term: **15 Years**

(21) Appl. No.: **29/670,867**

(22) Filed: **Nov. 20, 2018**

(30) **Foreign Application Priority Data**

May 25, 2018 (WO) DM/101485

(51) **LOC (12) Cl.** **07-99**

(52) **U.S. Cl.**

USPC **D7/392.1**

(58) **Field of Classification Search**

(57) **CLAIM**

The ornamental design for a lid, as shown and described.

DESCRIPTION

FIG. 1 is a perspective view of a lid showing my new design; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the lid that form no part of the claimed design.

1 Claim, 7 Drawing Sheets
